CLAIM

The ornamental design for a smartwatch, as shown and described.

DESCRIPTION

FIG. 1.1 is a front view of a smart watch in accordance with the present design;

FIG. 1.2 is a rear view thereof;

FIG. 1.3 is a left side view thereof;

FIG. 1.4 is a right side view thereof;

FIG. 1.5 is a top view thereof;

FIG. 1.6 is a bottom view thereof;

FIG. 1.7 is a perspective view thereof; and

FIG. 1.8 is another perspective view thereof.

The smart watch of the present design can be used for time-display, network communication, health monitoring, voice communication, and affairs processing, etc.

The broken lines in FIG. 1.6 indicate portions of the smart watch that form no part of the claimed design.

1 Claim, 8 Drawing Sheets
